John F. Battilane, Utica, New York

Des. Patent No. 207 dated Dec. 3, 1848

The schedule referred to in these letters patent, and
in the drawing, will be found.

Be it known that John F. Battilane of the City of Utica
and State of New York have produced a new ornamen-
tal design for an air tight parlor stove, and I do here-
by declare that the annexed drawing is a full & accu-
rate delineation of a stove constructed after my design
the side and back not shown being similar and
symmetrical with the side and front represented —
except that the back has the usual opening and
flanges for the applying and fitting of the pipe or
smoke flue to the same.

What I claim as my invention and desire to secure
as letters patent, is the combination & arrangement of
ornamental figures & forms represented in the accom-
panying drawing making an ornamental design
for an air tight stove.
